ROAD CHAIR

William E. White, Chicago, Ill., assignor to Kalman Steel Company, Chicago, Ill., a corporation of Delaware

Application January 9, 1931, Serial No. 507,656

6 Claims. (Cl. 94—8)

My invention relates to an accessory for road building and particularly to a novel support for the reinforcing bars used in pavements.

In concrete pavements as now designed, the outer edge is reinforced with one or more bars extending longitudinally and embedded in the concrete approximately six inches from the side edge. The problem of supporting the bars in the correct position prior to and during the pouring of the concrete has heretofore remained unsolved. To insure stability in structures used for that purpose, the common expedient has been adapted of providing a prong intended to be driven into the soil, but the variability of soils from soft sand to hard clay renders such supports uncertain. Other objections include instability under the impact of the mass of poured concrete, cost of construction, impediment to flow of concrete, and labor of installing. These objections have been overcome in the structure here disclosed.

The invention will be more readily understood by reference to the accompanying drawings, in which:

Fig. 1 is a view of a blank, showing the die operation necessary to produce two, duplicate chairs;

Fig. 2 is a perspective view of a completed chair;

Fig. 3 is a sectional view of a side form and bar showing the relation of the chair thereto; and

Figs. 4 and 5 are perspective views of slightly modified forms of the chair shown in Fig. 2.

A chair such as contemplated is installed in the position shown in Fig. 3, the letter A indicating the form used to define the lateral edge of the pavement, while the reinforcing bar is indicated at B. The chair C is of novel form and is constructed by the simple operations that will now be described.

In Fig. 1, I have shown a flat rectangular section of metal adapted to be acted upon by a cutting die and severed along the full lines shown in that figure. This results in waste of the cut-out parts indicated by the letter X and the production of two complete, identical blanks. This may be clearly seen by inverting the drawing containing Fig. 1.

After the die operation, the blanks are bent along the dotted lines 10, 11 of Fig. 1 and ribbed as at 12, 13, 14 of Fig. 2, thus producing the finished article shown in that view.

This article comprises a relatively broad flat base 15, the base including the portion 16 that normally occupied a portion of the space beneath the narrow brace 17. Thus the structure is stable having base portions on both sides of the stand-

ard or post 18. The standard has a seat 19 in its upper end for the bar B and is reinforced by the angular flange 20 that extends vertically along the outer edge. The flange is continued upwardly beyond the seat to provide a tongue 21 adapted to be hammered over the bar B, as shown in Fig. 3.

The brace extends diagonally downwardly from the upper end of the standard, terminating in a portion 22 having a vertical shoulder 23, the function of which, as best shown in Fig. 3, is to abut the lower edge of the form and provide a certain gauge for spacing the bar from the outer edge of the pavement. The base is continued laterally beyond the part 22 to provide a portion 24 adapted to be projected beneath the form. Thus when the chair is installed, it is held in position not only by its own stability, but by the weight of the form resting on the base.

The construction of Fig. 4 is the same as that already described, except that I provide a prong 25 at the corner of the standard. In cases where the user insists on some means for anchoring that end of the chair, such a prong may be easily formed.

The structure of Fig. 5 is likewise identical with that of Fig. 2 except that I provide an additional seat 26 for use where a double row of bars is required. This seat includes an additional tongue 27 adapted to be bent over a bar as already described.

The stability of the chair is assured regardless of the character of the subsoil, and the operation of placing it in position is quickly performed. The broad, flat base has the added function of insuring stability during the operation of pouring the concrete. The impact of the plastic mass settles the chair firmly into place and the weight of the concrete on the base avoids the possibility of lifting the bar and chair which frequently occurs if the chair is not securely anchored. The skeleton character of the chair insures the free flow of concrete and the complete imbedment of the bar.

The construction of the chairs is such that nesting is possible, a dozen or more being nested and tied for easy handling. The strength of the device is relatively great in proportion to the weight of the material employed and the small amount of waste involved in the forming operation, is a point of advantage in the construction cost.

I claim:

1. A road chair consisting of a section of sheet metal having a relatively broad flat base and a perpendicular post provided with a bar seat in

- its upper end, and a bracing arm extending diagonally from the base to the upper end of the post and integral with both. 80
2. A road chair consisting of a section of sheet metal having a relatively broad flat base and a perpendicular post provided with a bar seat in its upper end, and an angular flange on the post, the flange being extended upwardly beyond the seat and adapted to be bent over a bar in said seat. 85
3. A road chair including a flat base and a vertical standard at one end, the upper end of the standard providing a seat for a bar, an integral brace extending from the upper end of the standard to the opposite end of the base, the brace constituting a spacing gauge for positioning the bar relative to a form. 90
4. A road chair including a flat base and a vertical standard at one end, the upper end of the standard providing a seat for a bar, an integral brace extending from the upper end of the standard to the opposite end of the base, the brace constituting a spacing gauge for position- 95
- ing the bar relative to a form, said base having a portion extending beyond said brace and adapted to underlie a form. 100
5. A road chair formed from a single section of sheet metal without connecting operations, comprising a flat base, a standard rising from the base said standard having an angular side flange the upper end of which provides a bar-holding tongue, and a narrow brace in the plane of the metal of the standard, extending diagonally from the upper end of the standard to the base. 105
6. A road chair formed from a single section of sheet metal without connecting operations, comprising a flat base, a standard rising from the base said standard having an angular side flange the upper end of which provides a bar-holding tongue, and a narrow brace in the plane of the metal of the standard, extending diagonally from the upper end of the standard to the base, the metal originally in the space beneath the brace remaining as a part of the base. 110
